US0D1053496S

(12) **United States Design Patent** (10) **Patent No.:** **US D1,053,496 S**
(45) **Date of Patent:** **** Dec. 3, 2024**

(54) **STRONG BOX**

(71) Applicant: **Shenzhen Jianhui Technology Co., Ltd.**, Guangdong (CN)

(72) Inventor: **Jianhui Xue**, Guangdong (CN)

(**) Term: **15 Years**

(21) Appl. No.: **29/853,941**

(22) Filed: **Sep. 20, 2022**

(51) **LOC (14) Cl.** **99-00**

(52) **U.S. Cl.** **D99/28**
USPC **D99/28**

(58) **Field of Classification Search**

(57) **CLAIM**

The ornamental design for a strong box, as shown and described.

DESCRIPTION

FIG. 1 is a perspective view of a strong box showing my new design, in a closed position;
FIG. 2 is another perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof; and,
FIG. 9 is another perspective view thereof, shown in an open position.

The broken lines shown in the drawings represent portions of the strong box that form no part of the claimed design.

1 Claim, 9 Drawing Sheets
